UNITED STATES PATENT OFFICE.

JOSEPH L. JOYCE, OF NEW HAVEN, CONNECTICUT.

EGG-CARRIER.

SPECIFICATION forming part of Letters Patent No. 314,942, dated March 31, 1885.

Application filed February 2, 1885. (No model.)

To all whom it may concern:

Be it known that I, JOSEPH L. JOYCE, of New Haven, in the county of New Haven and State of Connecticut, have invented a new Improvement in Egg-Carriers; and I do hereby declare the following, when taken in connection with accompanying drawings and the letters of reference marked thereon, to be a full, clear, and exact description of the same, and to which said drawings constitute part of this specification, and represent, in—

Figure 1, a perspective view of a plate showing three rows of springs; Fig. 2, one of the springs detached; Fig. 3, a section through the plate, showing two springs introduced therein; Fig. 4, a reverse side of the plate.

This invention relates to an improvement in the construction of boxes or crates, such as employed for the transportation of eggs, the object being to construct the plates of the box with spring-clasps to hold and support the eggs, each independent of the other, and make the construction such that the springs may be introduced by machinery, and thereby greatly reduce the cost of the plates; and the invention consists in the arrangement of several wire springs for each egg, the springs being bent to shape to grasp the egg between their free ends, their other end introduced through the plate and bent down on the reverse side, as a means for securing and supporting the spring, and as more fully herein-after described.

A represents a single plate. I prefer to apply four springs to the support of each egg. These springs *a* are made from wire bent into shape, as seen in Fig. 2, their lower end, *b*, straight and bent from the body of the spring, so as to form a shoulder, as at *d*. These ends *b* are introduced through the plate, as seen in Fig. 3, the straight portion, which extends through the plate, bent back onto the plate, and as indicated in broken lines, Fig. 3, and as seen in Fig. 4. The hole through the plate to receive the ends of the springs should be such as to closely fit the springs, the shoulder *d* taking a bearing upon the upper side, and so that when the ends are turned back upon the reverse side of the plate the springs will be

firmly held in place, and each in proper relation to the other, as seen in Fig. 1. Each set of springs is arranged in as close relation to the next as may be and permit the eggs to rest therein without one coming in contact with another. The springs are curved outward from their lower ends upward and inward, so as to embrace the egg. Their upper ends grasp above the largest diameter of the egg, as indicated in Fig. 1. The wire springs readily yield in the introduction or removal of the eggs, yet are of sufficient strength to retain the egg in place under ordinary usage in transportation. By thus making the springs from wire and introducing one end through the plate, as a means for securing them to the plate, I am enabled to produce the plates with the springs complete by automatic machinery, which machine, however, constitutes no part of this present application.

The plate is best made from thin wood. The wire may be of small diameter, so that it is very light, and the plates with the springs attached are produced at a very small cost.

I have represented the plate and the springs thereon as arranged to receive several rows of eggs, and this construction I prefer; but each row may be made a separate plate.

I do not wish to be understood as claiming, broadly, the plate having springs arranged thereon to embrace and hold eggs, as such, I am aware, is not new.

I am aware of Patent No. 253,697, and do not wish to be understood as claiming anything therein shown or described; but

What I do claim is—
A plate having several sets of wire springs thereon, each set composed of several springs and each spring being a single wire, one end of each of said springs inserted through the plate and bent down upon the reverse side, the projecting portion of the said single springs bent outward on the upper surface of the plate and curved upward and inward, substantially as described.

JOS. L. JOYCE.
